UNITED STATES PATENT OFFICE.

THOMAS L. GREGSON AND JAMES I. PAYETTE, OF CHICAGO, ILLINOIS.

WIRE-STRIPPER.

1,113,986.

Specification of Letters Patent.

Patented Oct. 20, 1914.

Application filed May 26, 1913. Serial No. 769,831.

To all whom it may concern:

Be it known that we, THOMAS L. GREGSON and JAMES I. PAYETTE, citizens of the United States, residing at Chicago, in the county of Cook and State of Illinois, have invented a certain new and useful Improvement in Wire-Strippers, of which the following is a specification.

Our invention relates to improvements in wire strippers such as are adapted to remove the insulated covering from wires for use in connection with electrical devices and the like.

It is illustrated diagrammatically in two forms in the accompanying drawing, wherein—

Figure 1 is a plan view; Fig. 2 is a side elevation; Fig. 3 is an end elevation; Fig. 4 a section along the line 4—4 of Fig. 3; Fig. 5 a section along the line 5—5 of Fig. 3; Fig. 6 is a detail plan view of a modified form; Fig. 7 is a side elevation of the modified form shown in Fig. 6 with parts in slightly different arrangement.

Like parts are indicated by the same letter in all the figures.

The plier members A, A¹ are pivoted at A² and terminate each in cross blocks or cutter blocks B, B¹ at right angles to the plane of the handle. These cutter blocks B, B¹ are provided with grooves or slots B², B³ of such size to engage a so-called duplex conductor as shown diagrammatically at B⁴. Projecting inwardly from the bottom of each of these grooves are the knives B⁵, B⁶ which knives are adapted to split or cut on opposed sides the outer wrapping B⁷ of this duplex conductor. C, C¹ are smaller slots or grooves provided with similar knives C², C³ such as may be used for smaller duplex conductors or for stripping the wrapping from a single conductor. C⁴, C⁵ are knife edges at right angles to the cutting knives B⁵, B⁶, C², C³ adapted to assist in stripping or peeling off the wrapping or insulation after it has been cut by the knives in the bottoms of the grooves or slots. It will be noted that these cutting or splitting

knives are arranged in planes parallel to the plane of the pliers handles so that the operator can by drawing the pliers toward him, meanwhile holding firmly onto the ends of the wires, cut the insulation so as to leave the conductor free to be stripped and subsequently strip it by use of the stripping or scraping knives.

The use of the device is, of course, obvious as illustrated in the form shown in Fig. 2. In the modified form shown in Figs. 6 and 7, the operation is exactly the same, except that I have here shown these wire stripping blocks and knives as applied to the usual type of parallel jaw pliers as an attachment.

The plier handles D, D¹ are pivoted at D² and carry the jaws D³, D⁴. The stripper blocks D⁵, D⁶ are pivoted to the jaws D³, D⁴ by means of pivots D⁷, which pivots are perpendicular to the plier pivot D².

It will be noted that, as shown in Fig. 6, when the stripper blocks are out of operation, they lie down upon the jaws D³, D⁴ out of the way. When they are to be used, they are swung up to the position shown in Fig. 7, the end of the block abutting against the jaw D³ or D⁴ as the case may be, thus being limited against further rotation and compelled to project outwardly at right angles to the jaw. When in this position they operate in exactly the same manner as they do in the type shown in Figs. 1 and 2.

It will be evident that while we have shown in our drawings an operative device, still many changes might be made in the size, shape and arrangement of parts without departing materially from the spirit of our invention. We wish, therefore, that our drawings be regarded as in a sense diagrammatic.

We claim:

1. The combination with a pair of pliers of wire stripper blocks pivoted on said pliers, wire stripping means mounted in said blocks, said blocks being free to rotate through an angle of 90 degrees away from the pliers and means for limiting said rotation.

2. The combination with a pair of pliers of wire stripper blocks pivoted on said pliers, wire stripping means mounted in said blocks, said blocks being free to rotate through an angle of 90 degrees away from the pliers and means for limiting said rotation, said blocks being apertured and provided with opposed knives in said apertures.

Signed at Chicago, county of Cook and State of Illinois, this 17th day of May, 1913. 10

THOMAS L. GREGSON.
JAMES I. PAYETTE.
